UNITED STATES PATENT OFFICE.

PHILIP KLEIN AND HARLAND HUMPHREY, OF MANSFIELD, OHIO.

DETACHABLE SPRING-HINGE.

1,347,386.

Specification of Letters Patent. Patented July 20, 1920.

Application filed September 23, 1919. Serial No. 325,732.

To all whom it may concern:

Be it known that we, PHILIP KLEIN and HARLAND HUMPHREY, citizens of the United States, and residents of Mansfield, in the county of Richland and State of Ohio, have invented a new and Improved Detachable Spring-Hinge, of which the following is a full, clear, and exact description.

This invention relates to improvements in spring hinges and has reference more particularly to a hinge composed of two leaves, one of which is fixed to the door or window frame by means of offset flanges and a pivoted finger in such a way that it can be quickly removed.

An object of the invention is to provide a detachable spring hinge which will consist of only two parts, the part fixed to the door frame, and the part associated with the spring so that no spare parts will become lost when the hinge is not in use.

Another object of the invention is to provide a detachable spring hinge which will be cheap to construct and will allow the quick and easy removal of a door or window from its frame.

Reference is to be had to the accompanying drawing forming a part of this specification, in which it is understood that the drawing is merely illustrative of one example of the invention, and in which—

Figure 1 is a plan view of the detachable spring hinge assembled.

Fig. 2 is an end view of the detachable spring hinge.

Fig. 3 is a section through Fig. 1 on the line 3—3.

Fig. 4 is a plan view of the detachable part of the spring hinge.

Fig. 5 is a plan view of the fixed part of the detachable spring hinge.

Referring to the accompanying drawing by numerals, 10 indicates a leaf of a hinge which is fixed by any suitable means such as screws 11 to a door or window 12 and is pivoted by means of pin 13 through upstanding flanges 14 to another leaf 15. The spring 16 is coiled around the pin 13 and has two ends, one of which engages the leaf

10 and the other engages the leaf 15, so as to exert a constant force tending to rotate the leaves about the pin. Fixed to the door or window frame 17, by means of screws is a plate 18 on which is formed an offset flange 19, which extends into an opening 20 on the leaf 15, and engages a side of said

opening so as to fix the leaf 15 to the plate 18. A depending flange 21 is formed on the edge of leaf 15 opposite the opening 20 and assists the flange 19 in fixing the leaf 15 to the plate 18. A finger 22 is pivoted to the plate 18 by means of screw 23 and said finger may be rotated about its pivot until it engages the edge of an opening 24 in the leaf 15 so as to lock the leaf 15 to the plate 18.

Pivottally mounted in the upstanding flanges 14 of the leaf 15 is an operating bail 25 which terminates in offset ends 26 which coöperate with lugs 27 on plate 18 when the bail 25 is in one position, and with lugs 28 on said plate 18 when the bail 25 is rotated to substantially a diametrically opposite position.

When the ends 26 of the bail 25 are positioned back of the lugs 28, they serve as stops and the leaf 15 is further locked to the plate 18 thereby. When the bail 25 is swung about, the ends 26 first engage the plate 18 and thus lift the plate 15, so that the flange 21 is disengaged from the edge of the plate 18. Upon a continued rotation of the bail 25, the ends 26 engage the lugs 27 and thus translates the leaf 15 until the flange 19 is disengaged therefrom.

In use the leaf 10 is screwed to any door such as a screen door and the plate 18 is screwed to the door frame. When it is desired to put the door in place the leaf 15 is brought adjacent to the plate 18 so that the flange 19 engages the edge of the opening 20, and the flange 21 engages the edge of plate 18. The finger 22 is then rotated about its pivot 23 until it engages the edge of the opening 24. The bail 25 is then rotated so that the ends 26 engage the lug 28, thus locking the leaf 15 to the plate 18. When it is desired to remove the screen door between seasons the finger 22 is rotated about its pivot 23 until it is disengaged from the edge of opening 24 and the bail 25 is rotated through substantially 180 degrees so that the ends 26 engage the lugs 27, thus unlocking the leaf 15 from the plate 18 and permitting the withdrawing thereof.

The two leaves 10 and 15 and the plate 18 may be stamped from a sheet of metal and formed into the shape shown in the drawing by dies, but any other suitable construction may be used. While the illustrated example constitutes a practical embodiment of our invention, we do not limit ourselves strictly to

the mechanical details herein illustrated, since manifestly the same can be considerably varied without departure from the spirit of the invention as defined in the appended 5 claims.

Having thus described our invention, we claim as new and desire to secure by Letters Patent:—

1. A detachable spring hinge comprising a 10 pair of leaves pivoted together, spring means engaging said leaves arranged to rotate said leaves about a pivot, a fixed plate, interlocking means between said fixed plate and one of the hinge leaves, said interlocking means 15 including a finger pivotally mounted on said plate, the plane of rotation of said finger being parallel to the plane of the plate.
2. A detachable spring hinge consisting of two leaves pivoted together, one of said 20 leaves being fixed to a swinging member, a plate fixed to the frame of said swinging member, an opening in the other of said leaves, an offset flange formed on said plate arranged to engage the edge of said opening, 25 a depending flange formed on the edge of the last mentioned leaf and arranged to engage the edge of said plate, and a finger pivoted to said plate so as to engage the last mentioned leaf thereby locking said leaf to the plate. 30
3. A detachable spring hinge consisting of two leaves pivoted together, one of said

leaves being fixed to a swinging member, a plate fixed to the frame of said swinging member, an opening in the other of said leaves, an offset flange formed on said plate arranged to engage the edge of said opening, a depending flange formed on the edge of the last mentioned leaf and arranged to engage the edge of said plate, a finger pivoted to said plate so as to engage the last mentioned leaf thereby locking said leaf to the plate, and auxiliary means to lock the last mentioned leaf to the plate. 40

4. A detachable spring hinge consisting of two leaves pivoted together, means for fixing one of said leaves to a swinging member, spring means engaging each of said leaves so as to rotate them through a small arc about the pivot, a plate fixed to the frame of said swinging member, means for locking the other of said leaves to said plate, a pair of upstanding lugs on each end of said plate, and a bail-rod pivoted to the last mentioned leaf, the ends of said rod being offset so as to engage two of said lugs when in one position thereby locking said leaf to said plate and to engage the other two of said lugs when rotated to a second position thereby disengaging the plate from the last mentioned leaf. 50 55 60
